US00D570999S

(12) **United States Design Patent**
Harman et al.

(10) **Patent No.:** **US D570,999 S**
(45) **Date of Patent:** **** Jun. 10, 2008**

(54) **ROTOR**

(75) Inventors: **Jayden David Harman**, San Rafael, CA
(US); **Kimberly Penney**, Emeryville, CA (US)

(73) Assignee: **Pax Scientific, Inc.**, San Rafeal, CA
(US)

(**) Term: **14 Years**

(21) Appl. No.: **29/250,621**

(22) Filed: **Nov. 22, 2006**

(51) **LOC (8) Cl. 23-04**

(52) **U.S. Cl. D23/413**

(58) **Field of Classification Search** D23/370,
D23/379, 413; 416/223 R, 238, 243, 179,
416/182; 361/695

(57) **CLAIM**

The ornamental design for a rotor, as shown and described.

DESCRIPTION

FIG. 1 is a perspective view of the rotor, showing top and side views of the new design;

FIG. 2 is a top plan view of the rotor of FIG. 1;

FIG. 3 is a bottom plan view of the rotor of FIG. 1; and,

FIG. 4 is an enlarged side elevation view of the rotor of FIG. 1.
